(57) **CLAIM**

The ornamental design for a light clip, as shown and described.

DESCRIPTION

FIG. 1 is a first perspective view of a light clip showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the light clip thereof; and, FIG. 10 is a perspective view of another state of the light clip thereof.

The broken lines shown in the drawings depict portions of the light clip that form no part of the claimed design.

1 Claim, 10 Drawing Sheets
